SMOKING STAND

Arthur R. Visscher, Syracuse, N. Y.

Application August 19, 1954, Serial No. 31,933

Term of patent 14 years

(Cl. D85—2)

FIG. 2

FIG. 3

FIG. 1

FIG. 4

FIG. 6

FIG. 5

Figure 1 is a front elevational view of a smoking stand, showing my new design;

Figure 2 is a fragmentary top plan view thereof;

Figure 3 is a fragmentary side elevational view thereof, the ash tray being omitted;

Figure 4 is a fragmentary top plan view thereof partly in cross-section taken on line 4—4 in Figure 1;

Figure 5 is a fragmentary cross-sectional view thereof taken on line 5—5 in Figure 4; and

Figure 6 is a cross-sectional view thereof, to an enlarged scale, taken on line 6—6 in Figure 1.

I claim:

The ornamental design for a smoking stand, substantially as shown.
